C. DEAN.
LANTERN.

No. 96,897.

Patented Nov. 16, 1869.

UNITED STATES PATENT OFFICE.

CYRUS DEAN, OF BUFFALO, NEW YORK, ASSIGNOR TO JOHN ALEXANDER
BLAKE, OF PORT ROBINSON, CANADA.

IMPROVEMENT IN LANTERNS.

Specification forming part of Letters Patent No. 96,897, dated November 16, 1869.

To all whom it may concern:

Be it known that I, CYRUS DEAN, of Buffalo, in the county of Erie and State of New York, have invented a new and useful Combined Signal Lantern and Lamp; and I do hereby declare the following to be a full, clear, and exact description of the same, reference being had to the accompanying drawings, which are made part of this specification, and of which—

Figure 1 is sectional side elevation of a lantern illustrating my invention. Fig. 2 is a side elevation of the same.

Similar letters of reference indicate corresponding parts in the two figures.

The subject of this invention is more particularly intended for use as a signal-lantern for railroad-cars, but may be employed as a dark-lantern, or have some of the parts detached, and then constitute a common illuminating-lamp for domestic or other use.

The invention also includes a match-lighting device, which enables a person to light the lamp in the open air without exposing the ignited match to danger of extinguishment by the wind.

A may represent a lamp of any suitable construction. This lamp is provided with an annular flange, B, upon which rest the cylindrical glass and casing, which, as associated with the lamp, constitute either a signal or a dark lantern.

The lantern-glass C is fixed in position by means of a bottom flange, e, and upright rods h, said rods being fixed at top to an annulus, I, in the center of which is inserted a cap-covered tube, J. A metallic cylinder, D', encircles the upper part of the rods h, and is immovable thereon.

D is a movable cylindrical shield, which is fitted to slide upon the cylinder D' and upon the lower ends of the rods h. A bent rod, D'', is made fast to the sliding shield D, so as to form a bail or handle, whereby the shield D may be elevated or depressed, in order to either expose or entirely inclose the glass C, and thus diffuse the light, or wholly obscure the same. At opposite sides of the sliding shield D are circular openings, in which glasses of different color—say red and blue—may be inserted, as at D''. These colored glasses may be guarded by hinged doors, so as to permit no light to escape when the slide D is de-

pressed; but for signaling purposes either of these glasses may be exposed by opening its door when the slide is depressed, as aforesaid. It will thus be seen that by means of the sliding shield D, constructed and applied to the lantern-case as described, the device may be used as a signal-lantern or a dark-lantern, and that it may be made to afford a white effectively-illuminating light when not used for signaling. The flange B being coupled with the flange e by means of spring-elasps, the lantern-case, including the glass C, the sliding shield D, cylinder D', rods h, &c., may be readily detached from the lamp A, which, with its chimney A', may be then used as an ordinary illuminating domestic lamp.

When the lamp is combined with the lantern, as hereinbefore described, the lamp-chimney A' is inclosed by the lantern-glass C, a space existing between the two spaces to conduct the air downward from the top of the lantern to supply the flame. No air is admitted from below. The passage of the air downward to the flame and its exit upward through the chimney A' and cap-covered tube J are indicated by the arrows in Fig. 1.

A cup for heating water or other similar purpose may be substituted for the part J, suitable provision being made in that case to admit of the escape of the products of combustion in an upward direction.

E is a tube extending obliquely upward through the flange B of the lamp, and terminating at a point in proximity with the upper end of the wick-tube. The upper terminus of said tube is closed by a pivoted finger, F, whose surface may be roughened or in any way adapted to insure the ignition of a match when the same may be inserted through the tube and made to push the finger away from the upper mouth of the tube. The finger is made to offer a sufficient resistance to the thrust of the match by a spring applied in any suitable manner, said spring serving also to restore the finger to its normal position after the match has been withdrawn.

It is manifest that, inasmuch as the upper end of the tube E and finger F are inclosed within the lantern glass or casing, the wick may be ignited in the open air by a match passed upward through the tube E, notwithstanding the prevalence of strong winds.

Having thus described my invention, the

following is what I claim as new herein and desire to secure by Letters Patent:

1. The device herein described, consisting, essentially, of the lamp, the glass, the sliding shield, the signal-glass, and door, and adapted to be used as an ordinary lantern, a signal-lantern, or a dark-lantern, when these parts and their adjuncts are constructed as herein shown.

2. In combination with the above, the match-lighting attachment E F, constructed and applied as shown.

CYRUS DEAN.
